SALAD FORK OR THE LIKE

Alphonse La Paglia, Summit, N. J.

Application September 27, 1949, Serial No. 5,193

Term of patent 3½ years

(Cl. D54—12)

To all whom it may concern:

Be it known that I, Alphonse La Paglia, a citizen of the United States, residing at Summit, in the county of Union and the State of New Jersey, have invented a new, original, and ornamental Design for a Salad Fork or the like, of which the following is a specification, reference being had to the accompanying drawing, forming part thereof.

Fig. 1 is a front elevational view of a salad fork or the like showing my new design, and

Fig. 2 is a side elevation thereof.

I claim:

The ornamental design for a salad fork or the like, substantially as shown.

ALPHONSE LA PAGLIA.
